Primary Examiner—Cynthia E. Ramirez(74) *Attorney, Agent, or Firm*—McHale & Slavin PA(57) **CLAIM**

The ornamental design for a bagging ring, as shown and described.

DESCRIPTION

FIG. 1 is a perspective view of the bagging ring of the invention;

FIG. 2 is a front elevation view of the bagging ring of FIG. 1, the rear elevation view and left and right side views being identical thereto;

FIG. 3 is a top plan view of the bagging ring of FIG. 1; FIG. 4 is a bottom plan view of the bagging ring of FIG. 1; and,

FIG. 5 is a pictorial view of the instant invention shown on top of a platform for securing of a bag.

The platform and bag are for illustrative purposes only, and form no part of the claimed design.
